TWO-STROKE CYCLE INTERNAL COMBUSTION ENGINE

Michel Kadenacy, Paris, France

Application June 2, 1936, Serial No. 83,120
In Great Britain July 3, 1935

8 Claims. (Cl. 123—65)

This invention relates to two-stroke cycle internal combustion engines wherein at least a substantial portion of the burnt gases leaves the cylinder at a speed much higher than that obtaining 5 when an adiabatic flow only is involved, and in such a short interval of time that it is discharged as a mass leaving a depression behind it which is utilized in introducing a fresh charge into the cylinder by opening the inlet orifice with the 10 required delay after the opening of the exhaust orifice to ensure that the burnt gases are then moving outwardly through the exhaust orifice or duct and that a suction effect is exerted at the inlet orifice as a consequence of the exit of the 15 said mass.

An internal combustion engine of this type is described in the inventor's prior U. S. A. specification No. 2,102,559.

In such engines when the exhaust orifice first 20 commences to open there is a period of delay during which the gases do not emerge from the cylinder, and after this delay has elapsed the burnt gases issue as a mass, at high velocity, and by passing through the exhaust orifice form a 25 column moving rapidly in the direction of exhaust. Thereafter this outward movement is reversed in direction and a return of the gases towards the cylinder takes place.

If records of pressure variations in the exhaust 30 system are taken during the exhaust period by means which are also capable of indicating the direction of movement of the gases and which can respond to wide variations of pressure in short intervals of time, it can be determined 35 when this outflowing column of burnt gases has been formed, and it can also be determined when the mass of burnt gases commences to engage with the gaseous medium in the exhaust system and when the reversal in direction of movement 40 of the gases or return towards the cylinder takes place.

When the burnt gases leave the cylinder as a mass in the manner stated above, they leave behind them in the cylinder and in the exhaust 45 system, a void, the volume of which will depend upon the distance to which the mass of burnt gases travels away from the cylinder.

However if the reversal in direction of movement of the gases in the exhaust system occurs 50 before the exhaust closes, the inlet being still open, some of the charge may be forced out of the cylinder and foul gases may re-enter the cylinder.

In this connection it should be explained that 55 if the moment of reversal in direction of move-

ment of the gases at the exhaust orifice of the cylinder occurs when fresh gases have passed through the cylinder and have followed the burnt gases into the exhaust system thereby furnishing a valuable cooling effect which assists the engine 5 to operate at high outputs, the first effect of this reversal in direction will be to cause fresh gases to be forced back into the cylinder and this may be advantageous for the charging. These returning fresh gases will be followed by burnt 10 gases, and it is the subsequent re-entry of these burnt gases that will tend to foul the charge.

Further, if the reversal in direction of the gases occurs after a relatively long interval, expressed 15 in terms of crank angle, and the exhaust closes before this reversal occurs, then at the moment of closure of exhaust a depression will exist in the exhaust pipe close to the cylinder and consequently in the cylinder itself.

The object of the invention is avoid these two 20 objections.

The invention consists in closing the exhaust orifice of the cylinder before the return of the burnt gases into the cylinder occurs.

According to the invention the exhaust orifice 25 of the cylinder may be closed before the reversal in direction of the gases in the exhaust system adjacent the exhaust orifice occurs and the charging may be completed thereafter in any suitable manner.

Now the inventor has found that the time period elapsing between the mass exit of the burnt gases and the reversal in direction of movement 35 of these gases is substantially constant, and that as a consequence it extends over a larger crank angle at high engine speeds than at low engine speeds. Consequently at low speeds the charging 40 of the engine is more liable to be affected adversely by the return of the burnt gases to the cylinder which follows this reversal in direction and at higher speeds by a prolonged suction in the exhaust pipe.

According to the invention this objection may be overcome in a variable speed engine by closing 45 exhaust before the earliest return of the burnt gases to the cylinder occurs over the working range of speeds of the engine, whereby at low speeds the burnt gases are prevented from returning to the cylinder and at high speeds the prolonged suction existing in the exhaust system 50 is prevented from drawing the charge out of the cylinder. In this case also it may be advantageous to close the exhaust before the reversal in direction of the gases occurs and to complete the 55 charging after the exhaust has closed.

If it is desired to charge the engine by atmospheric pressure, it is evident that inlet must be opened not sooner than the moment the burnt gases commence to flow out as a mass and cause a suction to be exerted at the inlet orifice; and at varying speeds this moment of outflow will vary, as stated above.

Therefore according to the invention inlet should be opened not sooner than the moment (crank angle), when the latest outflow of the burnt gases commences, over a desired speed range.

The invention will be more fully described hereinafter with reference to the accompanying drawings, in which:—

Figure 1 shows curves of pressures existing in the exhaust pipe during the exhaust period of an engine to which the present invention has not been applied.

Figure 2 shows curves similar to those in Figure 1 taken on another engine to which the present invention has not been applied.

Figure 3 is a suitable timing diagram for applying the present invention to such engines.

Figure 4 illustrates an embodiment of an engine suitable for carrying the invention into effect.

Figure 5 shows a pressure indicating device;

Figure 6 shows one example of means for delaying the return of the burnt gases;

Figure 7 shows another example of means capable of delaying the return of the burnt gases.

The curves shown in Figures 1 and 2 were obtained by mounting on the exhaust duct an arrangement such as that shown in Figure 5 which comprises a device such as that described in United States application Serial No. 82,958 filed 1st June, 1936, and comprising a rotary ported sleeve 9 communicating through a port 10 with the interior of the duct 11 and surrounded by a fixed sleeve 12 having a port 13 corresponding with that in the rotary sleeve and connected to a manometer 14 suitable to permit pressures above and below atmospheric to be indicated.

If the rotary sleeve is rotated by the crank shaft of the engine, the ports in the fixed sleeve will coincide with those in the rotary sleeve for a given angular position of the crank shaft, whereby a pressure indication may be obtained. By making the fixed sleeve angularly adjustable, such readings may be taken at any desired intervals over the whole 360°.

Figure 1 shows a series of such curves taken at varying speeds on the exhaust pipe of a single cylinder opposed piston two-stroke engine having a capacity of 700 ccs. The observations were made at about 18 inches from the cylinder, and over 360°. In each case it will be noted that after a varying period of delay, the pressure in the exhaust pipe rises rapidly to a peak P and then falls suddenly to a maximum depression D after which the pressure again rises above atmospheric to a second peak P₁.

The first peak may be considered to be the point at which the burnt gases break down the external resistance and commence to leave the cylinder as a mass and this will be referred to as the moment of mass exit of the burnt gases from the cylinder. The point of maximum depression following this peak represents approximately the moment at which the direction of movement of the outflowing column is reversed. The return of the burnt gases following this reversal of flow may be considered to be complete at the second

peak P₁ of the curve after the depression has been destroyed.

The exact moment when the direction of movement at the exhaust orifice is reversed may be determined in the manner already indicated, and the precise moment when the burnt gases reach the exhaust orifice, in the case when they are preceded by fresh gases, can be determined by analysis of the gases in the exhaust system, at the exhaust orifice, for example by utilizing the means described above and replacing the manometer by a gas receiver.

It should be observed that if the record is taken close to the cylinder the first peak P will approach nearer to the angular position at which exhaust opens and the peak P₁ will move further away, since the gases will then have to travel a shorter distance outwards before reaching the point at which the record is taken and further to return to this point.

The point at which the curve descends below atmospheric pressure after the peak P does not necessarily indicate the exact crank angle at which the depression commences to form in the cylinder. It should be borne in mind that the gases are travelling outwards as a mass at a very high speed at this moment, as indicated by the small crank angle included between these two points of the curve, and that once the external resistance to the mass outflow of the gases has been overcome, the momentum of the outflowing mass will tend to prevent it from returning on its path should inlet be then opened. The peak P may be considered to be the point at which such outflow occurs and in considering the crank angle at which this peak occurs the distance at which the record is taken from the exhaust port should be taken into consideration.

In order to assist in determining the moment at which a suction commences to be exerted on the cylinder by the issuing gases, similar curves may be taken on the inlet duct.

The valve timing of the engine in question is shown in the figure, and it will be seen that at 900 R. P. M. (full line curve) and 1300 R. P. M. (dotted line curve) the return of the burnt gases into the cylinder occurs before exhaust closes and while inlet is also still open; whereas at 1500 R. P. M. (chain dotted curve), and at higher speeds, the return will occur after the exhaust has closed.

Figure 2 shows similar curves taken on a six-cylinder two-stroke engine of 7 liters capacity having piston operated inlet and exhaust ports situated at the same end of the cylinder, the timing of the ports being indicated in the figure and the record being taken at about 7 inches from the exhaust port. In this case the records were obtained at 1200 (full line curve), 1500 (dotted line curve) and 1800 (chain dotted curve) R. P. M., and it will be seen that at all these speeds the return into the cylinder occurs before exhaust closes and that at 1200 and 1500 R. P. M., the return occurs considerably before inlet closes.

It will therefore be seen that in order to avoid the fouling of the charge by returning burnt gases in the engines in question, it will be necessary to alter the timing so that at the particular working speed desired, the exhaust orifice of the cylinder is closed before the return of the burnt gases into the cylinder occurs.

If the exhaust orifice of the cylinder is closed before the reversal in direction of motion of the gases occurs the inlet orifice of the cylinder may remain open for the charging to be completed.

In this case as the exhaust is closed while the current of entering gases is still in motion in the direction of exhaust, this motion will assist the further entry of charge into the cylinder during the remainder of the charging period.

In order to apply these features of the invention to a variable speed engine, it will be necessary to close the exhaust orifice of the cylinder before the earliest return of the burnt gases to the cylinder or the earliest reversal in direction of motion of the gases in the exhaust system, and in both the examples shown in Figures 1 and 2, it will be seen that if the exhaust orifice is closed at bottom dead centre, the desired operation may be obtained at all speeds above the minimum speed represented by such timing.

In establishing a suitable closure of exhaust in the manner indicated above it should be borne in mind that it will not be profitable to attempt to close the exhaust immediately after the inlet has opened as this will prevent any utilization of the volume of the depression or void left in the exhaust system. It will, on the contrary be advantageous to maintain the exhaust open still further, as in this way the volume of the depression or void left in the exhaust system adds its action to that left in the cylinder and assists in the charging.

In order to enable the timing of inlet opening to remain suitable over a range of speeds of the engine, it will be necessary to ensure that at all these speeds inlet opens when the burnt gases are moving outwardly through the exhaust orifice or duct as a consequence of their mass exit from the cylinder and cause a suction effect to be exerted at the inlet.

By referring to Figure 1, it will be seen that as the speed of the engine increases, the angle that will elapse between the moment the exhaust orifice commences to open and the moment when a suction commences to be exerted in the cylinder as a consequence of the mass exit of the burnt gases will increase, although the variation in this angle for the range of speeds considered will not be so great as in the case of the return of the gases.

In order to ensure that the opening of inlet will remain suitable over the speed range considered it will therefore be necessary to establish the timing of inlet opening in such a way that the opening of inlet is suitable at the highest engine speed, thereby ensuring that it will also be suitable at all lower engine speeds.

More generally the inlet should be timed to open not sooner than the latest moment (crank angle) at which the mass exit of the burnt gases occurs over the speed range considered.

For the purpose of determining at any speed when the mass exit of the burnt gases commences it will be sufficient to determine the shortest lead of exhaust opening relative to inlet opening which will ensure that when inlet opens the exhaust gases will still issue through the exhaust duct and will exert a suction on the inlet duct.

If it is desired to delay the return of the burnt gases at low speeds in order to permit a later closure of exhaust, this may be effected, for example, by providing in the exhaust duct, sufficiently close to the cylinder, a chamber having reflecting surfaces therein so arranged as to impart to the mass of issuing gases a gyratory motion whereby the action of these gases on the external static gases and the duration of outward motion of the said gases are prolonged.

Figure 6 shows such an arrangement 15 being the said chamber and 16 reflecting surfaces adapted to impart helical motion to the gases about their axis of motion.

Or for the same purpose a by-pass chamber may be arranged on the exhaust duct close to the cylinder, this chamber being so arranged that the mass of burnt gases during its outward motion is directed past this chamber but so that the returning gases tend to enter this chamber. Figure 7 shows an engine cylinder provided with such an arrangement, 17 being the cylinder, 18 the inlet ports, 19 the exhaust ports communicating through a short neck 20 with the exhaust pipe 21, and 22 the by-pass chamber open to the pipe 21 at the free end of the neck 20. An exhaust pipe of suitable length and shape will also assist in delaying the return of the burnt gases. For example the exhaust pipe should preferably be outwardly flared and be of sufficient length that the return always occurs from a point within the exhaust pipe. If silencing means are provided these should not be placed nearer to the cylinder than the point of return.

Further it will be of interest to restrict the variations in the crank angles at which the exhaust gases leave the cylinder to a minimum.

This may be done by facilitating the exit of the gases by suitable port design and by reducing the frictional and other resistances to outflow in the exhaust duct to a minimum.

If at high speeds exhaust opens at a moment when the depression left by the preceding discharge still exists in the exhaust duct, the consequent reduction in the resistance to outflow will cause the burnt gases to issue sooner.

In a variable speed multi-cylinder engine this result may be obtained at relatively high speeds by a suitable arrangement of the exhaust ducts of the individual cylinders, and by suitably grouping the cylinders.

The effect of such an arrangement is shown in Figure 2 in which it will be seen that at 1800 R. P. M., exhaust opens at a moment when a depression exists in the exhaust duct, and the gases leave the cylinder earlier than at 1500 R. P. M.

An example of a suitable timing which will ensure that inlet opening and exhaust closure will occur in the desired manner over a wide range of speeds may be derived from the curves shown in Figures 1 and 2 and is represented in Figure 3.

In this figure it will be seen that exhaust opens at EO in the usual manner and inlet opens about 20° later at AO, whereby over the range of speeds indicated in the curve, inlet will always open at a moment when a suction is exerted upon the inlet by the depression left by the issuing exhaust gases.

Exhaust and inlet then remain open together for a period of time during which charging may be effected, if desired by atmospheric pressure.

A little before bottom dead centre, exhaust is closed at EC and the admission continues for recharging the cylinder up to a point AC established in a normal manner.

Such a timing gives an engine in which over a wide range of speeds above a predetermined minimum exhaust closes before the return of the burnt gases to the cylinder and in which inlet opens after the depression has commenced to exist at the inlet ports.

It should be noted that this timing is established from the curves shown in Figures 1 and 2

and that it may vary from one engine to another, according to the characteristics of the engine.

In considering the return of the gases, it should be noted that it is the action of this return on the contents of the cylinder that it is desired to avoid. For practical purposes it will be easy to select a moment for the closure of exhaust which will ensure that an objectionable action due to the return of the gases will be avoided, and it may be considered that this return may commence to be objectionable when the direction of outward movement of the gases in the exhaust system has been reversed and the burnt gases have reached the exhaust orifice of the cylinder.

For the purpose of completing the charging it may be of advantage to open a supplementary outlet at or about the closure of exhaust and before the closure of inlet.

If the engine is charged by atmospheric pressure this supplementary outlet may open to the atmosphere, whereby the inertia of the entering air may be employed to pass more air through the cylinder. Or the supplementary outlet may communicate with means whereby a suction is exerted on the cylinder in order to assist in drawing air through the latter.

The said supplementary outlet may for example open at SO a little after the closure of exhaust and close at SC a little before the closure of inlet.

If the charging is effected by atmospheric pressure and it is desired to apply a supplementary compressed charge, this supplementary charge will commence at CO, a little before the closure of the additional outlet, or a little before the closure of the main inlet, and will terminate at CC a little after the closure of the main inlet.

It should be noted that with a timing of inlet opening such as that indicated above the charge may be introduced by atmospheric pressure, but it is evident that if it is desired to introduce the charge under compression, this may be done without on that account going outside the scope of the invention.

One example of an engine suitable for carrying the invention into effect is illustrated diagrammatically in Figure 4, which shows a cylinder 1 in which moves a piston 2 controlling inlet ports 3 and exhaust ports 4 situated at the same end of the cylinder. Fuel is introduced into the cylinder by the injector 5 situated at the head of the cylinder. With such an engine the desired closure of exhaust may be obtained by controlling the passage through the exhaust duct by means for example of a rotary valve 6, which will be actuated in such a way that it will be open when the piston opens the exhaust ports 4 but will close before the piston on its return stroke has closed the ports 4. A suitable timing of inlet relative to exhaust in accordance with the invention may then be obtained by arranging for the exhaust port opening to lead the inlet port opening by the required amount.

A supplementary port 7 is provided at the opposite end of the cylinder to the ports 3 and 4. This supplementary port is controlled by a valve 8 which may be operated by any suitable means in order to open as an additional outlet as indicated in Figure 3, or to serve for the introduction of a supplementary compressed charge, as hereinbefore described.

I claim:

1. In a two-stroke cycle internal combustion engine of the kind described, a cylinder, a piston,

an inlet port at one end of the cylinder, an exhaust system, an exhaust port leading to the exhaust system, an additional outlet orifice situated at the opposite end of the cylinder to the inlet port, means for closing the exhaust port before the return of the burnt gases to the cylinder, means for subsequently closing the inlet port, and means for opening the additional outlet orifice about the time of closure of exhaust and for closing the said orifice about the time of closure of inlet.

2. In a two-stroke cycle internal combustion engine of the kind described, a cylinder, a piston, an inlet port at one end of the cylinder, an exhaust system, an exhaust port leading to the exhaust system, an additional outlet orifice situated at the opposite end of the cylinder to the inlet port, means for closing the exhaust port before the return of the burnt gases to the cylinder, means for subsequently closing the inlet port, and means for opening the additional outlet orifice a little before the closure of exhaust and for closing the said orifice a little before the closure of inlet.

3. In a two-stroke cycle internal combustion engine of the kind described, a cylinder, a piston, an inlet port at one end of the cylinder, and communicating to atmosphere, an exhaust system, an exhaust port leading to the exhaust system, an additional outlet orifice situated at the opposite end of the cylinder to the inlet port, means for closing the exhaust port before the return of the burnt gases to the cylinder, means for subsequently closing the inlet port, means for opening the additional outlet orifice about the time of closure of exhaust and for closing the said orifice about the time of closure of inlet, and means for supplying a supplementary compressed charge to the cylinder from a little before the closure of the additional outlet until a little after the closure of the atmospheric inlet.

4. A two stroke cycle internal combustion engine having a cylinder, exhaust and inlet orifices in the cylinder, an exhaust conduit on the cylinder, means for so controlling the exhaust orifice during the firing stroke as to ensure the issuance of the burnt gases as a mass, whereby the said mass moves outwards and thereafter returns from a point which may be within the said conduit, means for so controlling the inlet orifice as to ensure that it will be opened while the exhaust orifice is still open and when the said issuance of the burnt gases is in full progress and produces a suction effect in the cylinder, the said conduit providing a permanent free passage for the burnt gases to the limit of travel of said gases, means for closing the said exhaust orifice after the fresh charge has occupied the cylinder and before the instant when the pressure of the returning gases becomes effective within the cylinder.

5. A two stroke cycle internal combustion engine having a cylinder, exhaust and inlet orifices in the cylinder, an exhaust conduit on the cylinder, means for so controlling the exhaust orifice during the firing stroke as to ensure the issuance of the burnt gases as a mass, whereby the said mass moves outwards and thereafter returns from a point which may be within the said conduit, means for so controlling the inlet orifice as to ensure that it will be opened while the exhaust orifice is still open and when the said issuance of the burnt gases is in full progress and produces a suction effect in the cylinder, the said conduit providing a permanent free passage for the burnt gases to the limit of travel of said gases, means for closing the said exhaust orifice after the fresh charge has occupied the cylinder and before the instant when the pressure of the returning gases becomes effective within the cylinder.

the burnt gases to the limit of travel of said gases, means for closing the said exhaust orifice after the fresh charge has occupied the cylinder and before the instant when the pressure of the returning gases becomes effective within the cylinder, means for closing the inlet orifice subsequent to the closure of the exhaust orifice.

6. A method of controlling two stroke cycle internal combustion engines which comprises establishing communication between the cylinder and exhaust system during the firing stroke, providing for the issuance of the burnt gases as a mass, whereby the said mass moves outward and thereafter returns from a point which may be within the said system, providing a permanent free passage for the burnt gases to the limit of outward travel of said gases, preventing the entrance of fresh charging air into the cylinder until the said issuance of the burnt gases is in full progress, admitting fresh charging air into the cylinder when the said issuance of the burnt gases is in full progress and causes a suction effect to be exerted in the cylinder while the exhaust port is still open, providing for said fresh charge to occupy the cylinder in the interval elapsing between the mass exit of the burnt gases and the interval when the pressure of the returning gases becomes effective within the cylinder, shutting off the said communication between the cylinder and the said exhaust system after the said fresh charge has occupied the cylinder and before the instant when the pressure of the returning gases becomes effective within the cylinder, terminating the admission of fresh charging air after the said communication between the cylinder and the exhaust system has been shut off.

7. A method of controlling two stroke cycle internal combustion engines which comprises establishing communication between the cylinder and exhaust system during the firing stroke, providing for the issuance of the burnt gases, as a mass, whereby the said mass moves outward and thereafter returns from a point which may be within the said system, providing a permanent free passage for the burnt gases to the limit of outward travel of said gases, preventing the entrance of fresh charging air into the cylinder until the said issuance of the burnt gases is in full progress, admitting fresh charging air into the cylinder when the said issuance of the burnt gases is in full progress and causes a suction effect to be exerted in the cylinder while the exhaust port is still open, providing for said fresh charge to occupy the cylinder in the interval elapsing between the mass exit of the burnt gases and the interval when the pressure of the returning gases becomes effective within the cylinder, shutting off the said communication between the cylinder and the said exhaust system after the said fresh charge has occupied the cylinder and before the instant when the pressure of the returning gases becomes effective within the cylinder.

8. A method of controlling two stroke cycle internal combustion engines which comprises establishing communication between the cylinder and exhaust system during the firing stroke, providing for the issuance of the burnt gases as a mass, whereby the said mass moves outward and thereafter returns from a point which may be within the said system, providing a permanent free passage for the burnt gases to the limit of outward travel of said gases, preventing the entrance of fresh charging air into the cylinder until the said issuance of the burnt gases is in full progress, admitting fresh charging air into the cylinder when the said issuance of the burnt gases is in full progress and causes a suction effect to be exerted in the cylinder while the exhaust port is still open, providing for the said charge to occupy the cylinder and a portion of the exhaust system in the interval elapsing between the mass exit of the burnt gases and the instant when the pressure of the returning gases becomes effective within the cylinder, shutting off the said communication between the cylinder and the exhaust system after the fresh charge has occupied the cylinder and a portion of the exhaust system and before the instant when the pressure of the returning gases becomes effective within the cylinder.

the cylinder when the said issuance of the burnt gases is in full progress and causes a suction effect to be exerted in the cylinder, while the exhaust port is still open, providing for the said fresh charge to occupy the cylinder in the interval elapsing between the mass exit of the burnt gases and the interval when the pressure of the returning gases becomes effective within the cylinder, shutting off the said communication between the cylinder and the said exhaust system after the said fresh charge has occupied the cylinder and before the instant when the pressure of the returning gases becomes effective within the cylinder, terminating the admission of fresh charging air after the said communication between the cylinder and the exhaust system has been shut off.

9. A method of controlling two stroke cycle internal combustion engines which comprises establishing communication between the cylinder and the exhaust system during the firing stroke, providing for the issuance of the burnt gases as a mass, whereby the said mass moves outward and thereafter returns from a point which may be within the said system, providing a permanent free passage for the burnt gases to the limit of outward travel of said gases, preventing the entrance of fresh charging air into the cylinder until the said issuance of the burnt gases is in full progress, admitting fresh charging air into the cylinder when the said issuance of the burnt gases is in full progress and causes a suction effect to be exerted in the cylinder, while the exhaust port is still open, providing for the said charge to occupy the cylinder and a portion of the exhaust system in the interval elapsing between the mass exit of the burnt gases and the instant when the pressure of the returning gases becomes effective within the cylinder, shutting off the said communication between the cylinder and the exhaust system after the fresh charge has occupied the cylinder and a portion of the exhaust system and before the instant when the pressure of the returning gases becomes effective within the cylinder.

MICHEL KADENACY.
